UNITED STATES PATENT OFFICE.

CHARLES CAILLE, OF LE PERREUX, FRANCE.

DOUBLE-ACTION FEED-PUMP FOR STEAM-GENERATORS OR OTHER APPLICATIONS.

SPECIFICATION forming part of Letters Patent No. 739,828, dated September 29, 1903.

Application filed May 1, 1903. Serial No. 155,221. (No model.)

To all whom it may concern:

Be it known that I, CHARLES CAILLE, engineer, of 7 Rue des Vignes, Le Perreux, in the Republic of France, have invented a certain 5 new and useful Double-Action Feed-Pump for Steam-Generators or other Applications; and I do hereby declare the following to be a full, clear, and exact description of the invention, such as will enable others skilled in the art to 10 which it appertains to make and use the same.

In my Patents Nos. 714,096 and 714,097, of November 18, 1902, I have described an apparatus for forcing liquids, consisting of a pump-cylinder in which the filling takes place 15 automatically by means of simple descent of liquid under a head into the cylinder of the pump from a reservoir during the upward or return stroke of the piston, the water entering below or in front of this latter, this automatic filling without counter-pressure of air and vaporized liquid being rendered possible by means of a free passage to the atmosphere through a communication which opens automatically when the liquid enters and shuts 25 automatically directly the piston begins its working stroke. I then described two forms for the practical application of this principle.

The present application for a patent is for the purpose of securing the rights to a new 30 arrangement in which the same principle is extended to the employment of a double-action pump.

A form of the new construction is represented in detail on the accompanying drawings, in which—

Figure 1 is a sectional elevation of the whole. Fig. 2 is a section through A B C D of Fig. 1. Fig. 3 is a partial section through E F of Fig. 1. Fig. 4 is a section through G H I of Fig. 3. 40 Fig. 5 represents a part sectional elevation of the double-action feed-pump combined with an arrangement for varying the discharge and at the same time avoiding any admission of air into the generator, the pump being directly operated by the movement of the engine-shaft.

The apparatus consists in principle of the pump-cylinder itself, *f*, which is provided at its lower end with a spring-closed valve *c*, 45 forming the discharge-valve, admission to the cylinder taking place through an annular recess and a circle of openings *o*. Above this

circle the pump-cylinder is prolonged into a cylinder *a*, also made to fit the piston *p*, which, as will be seen later, is characterized in this way, that in its downward stroke it is simply a piston, while in its upward stroke it is at the same time a piston and the movable barrel of a pump. For this purpose it is made in the form of a hollow vessel, as is indicated 55 in Fig. 1, and its rod *b* is led through a projection *d* of the cover *e*. This projection nearly fills up the hollow of the piston; but between it and the piston there is an annular space *k*.

A casing *j* incloses the pump-cylinder *f*, forming around it a chamber *l*, Fig. 2, which communicates with the atmosphere by means of a pipe *t*, which pipe is raised above the level of the water in the feed-reservoir. This 60 chamber does not communicate with the discharge-passage *g*. In this latter is placed a spring-loaded valve *m*, which separates it from the hollow *h* of the piston *p* and chamber *n*. A pipe *q*, in communication with the atmosphere, is led away from this chamber *n*, but is separated from it by a floating valve *r*. The water coming from the feed-reservoir enters the apparatus by the pipe *i*, Figs. 3 and 70 4, and fills the chamber *l*, from whence it rises 80 in the pipe *t* up to the level of the water in the reservoir.

Suppose the mechanism to be in the position shown in Fig. 1. The piston *p* is at the top of its upward stroke and the hot water 85 with which the chamber *l* is filled descends through the openings *o* into the pump-cylinder *f*. The air-bubbles and steam produced from the hot liquid escape into the pipe *t*, where they condense. When the piston in 90 its downward stroke covers the openings *o*, the forcing of the water in the cylinder of the pump takes place through the pipe *g* on account of the valve *c* being pressed down. When the piston is at the end of its stroke, 95 the upper edge of the hollow piston uncovers the openings *o* and the hollow becomes filled with hot water in the same way that the pump-cylinder *f* was filled. The water flowing in also fills the chamber *n*, while the 100 steam formed can escape into the pipe *q* through the floating valve *r*, which now falls away from its seating by the action of its own weight. Directly the piston *p* is rising again

recovers the openings *o* it forces the water from the hollow *h* and the chamber *n*. The sectional area of the annular space *k* is equal to the opening of the valve *m*. This opens and 5 the liquid forced during the upward stroke escapes through the pipe *g*. The floating valve *r* shuts by the buoyancy of the water immediately the chamber *n* is entirely filled with water and freed of steam.

10 The piston *p* of the feed-pump in certain installations receives its motive power by a transmitter connected with the shaft of the main engine instead of being operated by an auxiliary engine. In this case since the number 15 of revolutions of the engine are maintained constant by a governor, while the supply of feed-water must be varied in proportion to the work required of the engine, it is indispensable to be able to vary the discharge 20 of the feed-pump by checking the water-supply. If while this checking is taking place the pipes *q* and *t* were left open to the air, the consequence would be that, the pump-cylinder *f* not being entirely filled with water, 25 air would be forced into the boiler. Such an operation would be objectionable. To avoid this disadvantageous action, the simple arrangement represented in Fig. 5 is connected with the feed-pump. In the example represented 30 in this figure the piston-rod *b* of the feed-pump *j* is connected by a transmitter 2 3 4 5 6 to the shaft 1 of the engine. The water coming from the tank *v* before entering the feed-pump by the pipe *i* flows down a 35 pipe *u* into a heating arrangement *x*. The waste steam from the engine-exhaust enters this heater through *w* and after being condensed escapes through *z*. The heated water flows through the pipe *y*, connected to the 40 admission-orifice *i*, after passing through a valve *s*. The pipes *t* and *q* instead of being open to the air open into the upper portion of a receiver 7, placed above the heater *x* and into which the water rises to the level of the water 45 in the tank *v*. At the upper end of the pipe 8, which connects the heater with the receiver, is placed a non-return valve 9. At the top of the receiver 7 is placed a valve 10, which tends to be held constantly open from 50 within outward by the action of a spring.

In the ordinary working, since the valve 10 is always raised, the steam arising from the cylinder of the pump escapes into the air through the top of the receiver 7. If the entry of the water into the feed-pump is checked 55 by means of the valve *s*, the pump-cylinder *f* becomes only partially filled with water, and the downward stroke of the piston *p* causes an aspiration in the pipes *q* and *t*; but 60 at the same time a similar aspiration is produced in the chamber 11, the valve 10 shuts under atmospheric pressure, and only the steam given off by the water in the receiver 7 is drawn into the pump.

65 In the case when the feed-pump works by

suction without pressure it may happen that the steam given off in the chamber 11 by the liquid of the receiver 7 is not at atmospheric pressure. The result would be an aspiration of water from the heater into the pipes *t* and *q*. This aspiration is rendered impossible by the non-return valve 9, which then presses against its seating, while normally it is held down by a spring in order to give free passage to the water.

75 It is apparent that with an apparatus as described a double-action feed-pump is obtained capable of forcing water or any liquid at any temperature without the possibility of the steam rising from the hot liquid being able to hinder in any way the operation or supply of the apparatus.

I claim—

1. An apparatus for forcing liquids, consisting of a pump-cylinder *f*, a cylinder *a* forming an extension of said cylinder *f*, an opening *o* between said cylinders, a chamber *l* communicating with said opening, said chamber being connected to a source of supply, a piston *p* formed with a chamber in its upper part, a chamber *n* above said piston connecting with the chamber in said piston, and a discharge-pipe connected to the chambers formed in the cylinders *a* and *f* whereby on the downward stroke of the piston the water in the chamber in the cylinder *f* will be discharged and on the upward stroke the water in the chamber *n* will be discharged, the water flowing into one chamber while the water in the other chamber is being discharged. 95

2. An apparatus for forcing liquids, consisting of a pump-cylinder *f*, a cylinder *a* forming an extension of said cylinder *f*, an opening *o* between said cylinders, a chamber *l* communicating with said opening, said chamber *l* being connected with a source of supply, a discharge-pipe *g*, a valve *c* in the bottom of cylinder *f*, connecting said cylinder with the pipe *g*, a pipe *t* located in the top of chamber *l*, a piston *p* formed with a chamber in its upper part, said piston being adapted to slide in the cylinders *a* and *f*, a projection *d* extending down into the cylinder *a*, said piston having a stem which passes through said projection, a chamber *n* between the cylinder *a* and the projection *d*, said chamber *n* connecting with the chamber in the piston, a passage extending from the chamber *n* to pipe *g*, a valve *m* controlling said passage, a pipe *q* located in the upper part of the chamber *n*, and a floating valve *r* in said pipe. 115

In testimony whereof I have hereunto set my hand in the presence of two subscribing witnesses.

CHARLES CAILLE.
